UNITED STATES PATENT OFFICE.

WILLIAM A. TAYLOR AND PHILIP J. SIBLEY, OF CHICAGO, ILLINOIS, ASSIGNORS TO
PHILIP J. SIBLEY, OF CHICAGO, ILLINOIS.

VAPOR TREATMENT RECEPTACLE.

Application filed April 23, 1923. Serial No. 633,900.

To all whom it may concern:

Be it known that we, WILLIAM A. TAYLOR and PHILIP J. SIBLEY, both citizens of the United States, residing at Chicago, in the county of Cook and State of Illinois, have invented certain new and useful Improvements in a Vapor Treatment Receptacle, of which the following is a specification.

This invention relates to a steam or vapor treatment apparatus particularly designed and intended for treating the feet although it may have a more general use wherever applicable. The principal object of the invention is to provide a simple, new and improved receptacle for containing the body member to be treated, the containing receptacle for the vaporizing fluid, and for preventing the escape of the treatment features. Other objects will appear herein-
20 after.

In the accompanying drawing, Fig. 1 is an elevation of a treatment receptacle embodying the features of this invention; Fig. 2 is a sectional view; and Fig. 3 is a plan view.

In treating the feet by a vapor method it is desirable not only to retain the vapor applied to the feet, but also to provide means for protecting the feet from contact with the vaporizing liquid at times, and also to immerse the feet in the same or other liquid when desired. A metal container or receptacle is unsatisfactory for this purpose because it is too good a conductor of heat and causes burning or discomfort to any part of the body to which the metal comes in contact.

In the present invention there is an outer receptacle 1 preferably in the form of a circular tub or pail. This receptacle is provided in the ordinary manner with top and bottom fastening hooks 2 and 3 and opposite sides handles 4. A lifting bail or handle 5 is also pivoted on opposite sides and may be provided with a hand grip 6. A top or cover 7 is provided with a hinge 8 on one side and opposite this side are 2 approximately semi-circular recesses 9 cut in from the edge of the cover to provide for the insertion of a person's feet within the top or receptacle.

In the bottom of the receptacle 1 is a shallow wooden tub 10 provided with a re-

movable cover 11, the edge of which is formed at intervals with notches 12 to provide hand holes for removing this top and also to allow for the escape of vapor from the shallow tub 10. A number of holes 13 are also provided in the sides of this tub adjacent the top thereof to allow the escape 60 of vapor from a liquid contained in the shallow tub.

In operation the shallow receptacle or tub 10 is filled with a hot liquid, which may consist of some medical compound that will give off vapors of certain kinds. The cover 11 is then placed upon the shallow top, the feet are inserted in the receptacle 1 and may be raised upon the cover 11, the lid 7 is closed, and any space between the openings 70 9 and the legs of a person are properly closed by placing a towel around the legs on top of the lid so that the vapor can not escape. The receptacle 1 will be full of vapor from the shallow tub 10 and after 75 keeping the feet in this vapor a time, ten or fifteen minutes, the contents of the shallow tub 10 is emptied into the receptacle 1 and about two gallons of water as hot as the patient is able to stand is placed in the receptacle. The feet are then again placed in the receptacle 1 as before where they are soaked for fifteen or twenty minutes longer.

This apparatus is simple in construction and use, it being made of wood, the containers do not become so objectionably hot as to burn the body of a patient with which they come in contact. Furthermore, the wood absorbs more or less of the vaporized liquid, increasing the medicinal vaporizing 90 effect as it is used.

We claim:

In a foot treatment apparatus, a wooden receptacle having a lid with recesses in the edges thereof to admit and partially surround the legs of a patient, a shallow tub for the bottom of the receptacle having perforations adjacent the top to permit the escape of vapor, and a wooden cover for the shallow tub providing recesses in the edges 100 by means of which the cover can be removed, the cover providing a support for the feet of a patient.

WILLIAM A. TAYLOR,
PHILIP J. SIBLEY.
